(57) **CLAIM**

The ornamental design for a closed compression-type coaxial cable connector, as shown and described.

DESCRIPTION

FIG. 1 is a front perspective view of a closed compression-type coaxial cable connector showing our new design; FIG. 2 is a back perspective view thereof;

FIG. 3 is a top plan view thereof, the bottom plan view being a mirror image thereto;

FIG. 4 is a left side view thereof, the right side elevation view being a mirror image thereto;

FIG. 5 is an enlarged front elevation view thereof; and, FIG. 6 is an enlarged back elevation view thereof.

The broken lines shown represent unclaimed subject matter only and form no part of the claim. Where broken lines abut a claimed surface it is understood that those broken lines represent an unclaimed boundary between claimed and unclaimed surfaces. None of the broken lines form any part of the claimed design.
